[57] CLAIM

The ornamental design for an automobile security
alarm, as shown and described.

DESCRIPTION

FIG. 1 is a front elevational view of my design for an
automobile security alarm;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view thereof, with the cord
broken away to indicate indeterminate length and with
the broken line of the adaptor showing for illustrative
purposes only and forming no part of the claimed de-
sign; and,

FIG. 8 is a perspective view thereof, with the adaptor,
lock ring and transmitter showing for illustrative pur-
poses only and forming no part of the claimed design.

FIG. 1.

FIG. 2.

FIG. 3.

FIG. 4.

FIG. 5.

FIG. 6.

FIG. 7.

FIG. 8.
